J. L. MURPHY,
COLLAR AND SUPPORT.
APPLICATION FILED FEB. 26, 1918.

1,303,363.

Patented May 13, 1919

UNITED STATES PATENT OFFICE.

JAMES L. MURPHY, OF CHICAGO, ILLINOIS.

COLLAR AND SUPPORT.

1,303,363.

Specification of Letters Patent. Patented May 13, 1919.

Application filed February 26, 1918. Serial No. 219,197.

To all whom it may concern:

Be it known that I, JAMES L. MURPHY, a citizen of the United States, residing at Chicago, in the county of Cook and State of Illinois, have invented certain new and useful Improvements in Collars and Supports, of which the following is a description.

My invention belongs to that general class of articles known as wearing apparel and particularly to collars. More particularly it relates to that class known as soft collars and supports therefor, and has among its objects the production of a collar support and collar of the kind described that is simple, convenient, comfortable, attractive, slightly, durable, efficient and satisfactory. It has particularly as an object the production of a supported soft collar which will keep its shape at the front and not wrinkle, which will always fit perfectly, one in which the necktie will pull or slide easily, and which may be easily and perfectly laundered and be extremely durable. The invention has as a special object the production of a supporting or stiffening member suitable for use with any style of soft collar, which supporting device is simple, may be easily applied or detached from the collar and which may be manufactured at small cost. Many other objects and advantages of the collar and supporting member herein shown and described will be obvious to those skilled in the art from the disclosure herein given.

To this end my invention consists in the novel construction, arrangement and combination of parts herein shown and described and more particularly pointed out in the claims.

In the drawings, wherein like reference characters indicate like or corresponding parts,

Figure 1 is a perspective view of my collar with supporter applied thereto;

Fig. 2 is a view in elevation of a portion of the collar with the parts turned back to show the construction;

Fig. 3 is a sectional view taken substantially on line 3—3 of Fig. 1;

Fig. 4 is a sectional view through the supporter enlarged to show the hinge construction; and

Fig. 5 is a view similar to Fig. 2 illustrating another method of attaching the supporter.

Referring to the drawings, 1 represents

the inner part or band of the collar formed with the end 2, one of which is arranged to overlap the other, 3 and 4 being button holes by means of which the band 1 is secured to the shirt neck band with the usual collar buttons (not shown), or their equivalents. In addition to the button holes 3 and 4, I prefer to provide co-operating fasteners 5 and 6, preferably of the ball and socket type similar to glove fasteners, so that the two upper edges of the band 1 may be secured together and maintained in place. Secured to the band 1, or formed therewith in any suitable manner, is the outer or rolled over part 8 of the preferred size, shape and style, this varying in different collars depending upon the individual preference of the wearer.

My preferred support, stay or retaining member consists of the parts 8 and 9, preferably of pyralin, celluloid or the equivalent for the purpose, that is flexible or resilient and will not rust or corrode, the same being of the desired size and shape. These two parts are hinged together in any suitable manner. As shown, they are suitably covered and incased in the tape 10 and 11, it being understood that any material found suitable may be used for the covering. I prefer to space the adjacent ends substantially as shown in Fig. 4 and stitch or sew the same as at 12, so as to provide the portion 13, which may be termed the "hinge". I have shown two lines of stitching, but obviously the parts 8 and 9 would be retained in their respective compartments and the hinge formed with only one line of stitching, or the stitching may be entirely omitted. The omission, however, is not preferred. The length of the sections 8 and 9 of course depends upon the size of the collar, and the width may be as desired. Referring to Fig. 2, it will be noted that the hinge is formed at an angle so that the support lies substantially parallel with the front edge of the portion 7.

I detachably secure the collar and support together by means of the parts 14, 17 and 20 or their equivalents for the purpose. These parts ordinarily are made of cloth, tape or the like. Part 14 is stitched to the band 1 at 15, the side adjacent the end 16 being open. Part 17 is stitched to the part 7 at 18, the same being open at both edges 19, and part 20 is stitched at 21 and open at 110.

22. Obviously if all were stitched as part 17, this part would engage at the hinge and retain the stay and prevent its dropping down to display the extreme ends. I prefer, however, to form parts 14 and 20 in the shape of pockets as shown. In the construction shown in Fig. 5, the supporter is similar to that shown in the other figures. In lieu of the parts 17 and 22, however, I cut 10 a slot or slit 26 in the part 25 of the collar and insert the supporter between the parts 25 and 25' of the rolled over portion of the collar, it being customary to make this portion of several plies or layers of material. 15 A part similar to 14 is arranged on the inner band 1' adjacent the free end 2' as shown. It will be noted that in both forms a portion of the support is displayed, upon which may be inscribed the words "Remove 20 before laundering," or words of like import. Obviously a collar provided with my supporting member will always keep its shape at the front and not become wrinkled or bent, but, however, because of its flexibility 25 and resiliency it will give but return to its normal position. The support does not show nor does it come in contact with the neck of the wearer, and will not rust or corrode or discolor the collar. It is easily and 30 quickly removed or replaced when the collar is laundried, the collar being of light weight and of a minimum amount of material may be laundried easily.

Having thus described my invention, it is 35 obvious that various immaterial modifications may be made in the same without departing from the spirit of my invention, hence I do not wish to be understood as 40 limiting myself to the exact form, construction, arrangement and combination of parts

herein shown and described or uses mentioned.

What I claim as new and desire to secure by Letters Patent is:—

1. A collar support consisting of two 45 parts arranged with their ends adjacent, a covering incasing said parts and constituting a hinge at said ends, said support detachably secured to the collar parts between the inner band and the turned over portion 50 and adjacent the ends thereof.

2. A collar support consisting of two parts arranged with their ends adjacent, a covering incasing said parts and constituting a hinge at said ends, said support detachably secured to the collar between the inner band and the turned over portion and adjacent the ends thereof, the ends of the support cut substantially parallel with the adjacent outer lower edges of the inner band 60 and said rolled over portion.

3. In a collar of the kind described having inner and outer portions and in combination, a supporting member for the outer meeting edges of said portions arranged adjacent the ends of the collar, said member consisting of two parts hinged together intermediate their ends, one part secured to the inner portion of the collar adjacent the free edge and the other part detachably secured to the other portion of the collar between its edges.

In testimony whereof, I have hereunto signed my name in the presence of two subscribing witnesses.

JAMES L. MURPHY.
